The ornamental design for a combined tooth brush holder and brushing timer, as shown and described.

DESCRIPTION

FIG. 1 is a front elevational view of a combined tooth brush holder and brushing timer showing my new design, the rear being a mirror image of that shown; FIG. 2 is a top plan view thereof;

FIG. 3 is a side elevational view thereof, the opposite side being identical in appearance; and,

FIG. 4 is a bottom plan view thereof.

FIG. 1

FIG. 2

FIG. 3

FIG. 4
